UNITED STATES PATENT OFFICE.

PRESTON BELVIN, OF RICHMOND, VIRGINIA.

AUXILIARY FASTENER FOR DOORS.

Application filed September 30, 1925. Serial No. 59,637.

This invention relates to auxiliary locking devices for doors. Doors, as ordinarily hung, are not securely locked for the reason that even though a high grade lock be employed at the free side of the door, the door can be opened by removing the pintle pins of the door hinges and then bodily displacing the door. Therefore, the present invention has, as its primary object to provide means for preventing such displacement of the door in the event an attempt is made to open the same by removing the pintle pins of the hinges.

Another object of the invention is to provide an auxiliary locking device for doors which may be readily applied to any door already hung without the necessity of taking down the door and which device will securely hold the door at its hinged side against outward displacement from its frame, the ordinary lock serving its usual function of preventing outward displacement of the free side of the door.

Another object of the invention is to provide a device for the purpose stated which will serve not only as an auxiliary locking means for the door but also as a means for preventing sagging or settling of the door in its frame.

30 In the accompanying drawings:

Figure 1 is a perspective view illustrating one embodiment of the invention adapted to a door.

35 Figure 2 is a horizontal sectional view illustrating the embodiment shown in Figure 1, the door and its frame being likewise shown in section and the door being closed.

40 Figure 3 is a view similar to Figure 2, illustrating a somewhat simplified form of the invention.

Figure 4 is a perspective view illustrating the embodiment of the invention in a hinge.

In the embodiment of the invention illustrated in Figures 1 and 2 of the drawings, the device is illustrated as comprising a locking member indicated in general by the numeral 1, and a keeper member indicated in general by the numeral 2. The locking member 1 comprises a rectangular plate 3 which is mortised in the edge of the door, which is indicated by the numeral 4, and secured in place by screws 5, the door being hung by the usual hinges 6 within the door frame 7. At its upper or lower end the plate 1 is provided with an integral locking finger 8 which is of arcuate form and, in the

closed position of the door, is engaged through a slot 9 formed in the keeper member 2 and projects into a recess 10 formed in the jamb of the door frame upon which the door is hung, as best illustrated in Figure 2 of the drawings. It will be observed by reference to Figure 2, that the finger 8 is flat-sided and that its edge which is the more remote from the pintles of the hinges and which edge is indicated by the numeral 11, is concentric to the axes of the pintles of the hinges. The other arcuate edge of the finger, indicated by the numeral 12, is curved on an arc such that the finger will readily enter the slot 9 when the door is swung to closed position, but on such an arc that when the door is in full closed position, the said edge 12, at the inner end of the finger, will snugly engage against the adjacent end wall 75 of the slot 9, thereby preventing any play or looseness if the pintle pins of the door hinges should be removed in an attempt to open the door. This is, of course, of importance inasmuch as if there should be any appreciable play between the parts, the one attempting to surreptitiously open the door would be influenced to use a tool of some kind to take advantage of the loose fit between the parts in an attempt to pry open the door. It will be observed by reference to Figure 1 of the drawings that the slot 9 is of a width substantially not greater than the thickness of the locking finger 8, so that when the door is closed, the finger will fit, 80 at its inner end, more or less snugly within the slot, thereby preventing any sagging of the door at its hinged side, and, therefore, the device serves not only its initial function of locking the door in a manner to prevent opening thereof in the event the pintle pins of the hinges are withdrawn but, it serves also as a means to prevent sagging of the door at its hinged side.

It is preferable that the keeper shown in Figures 1 and 2 of the drawings be employed for the reason that it adds to the security of the locking device, but, if desired, the keeper may be omitted, as illustrated in Figure 3 of the drawings, and the door jamb 90 may be merely formed with a socket indicated by the numeral 13, to accommodate the locking finger which, in this figure, is indicated by the numeral 14 and corresponds in every respect to the finger 8 of the previously 95 described form. In this instance, the recess 13 will be so formed that the concave edge 100

15 of the locking finger corresponding to the edge 12 in the previously described form, will engage against one wall of the recess, in closed position of the door, so as to prevent any play between the parts.

5 In the previously described forms of the invention the auxiliary locking device is independent of the hinges for the door, but in the embodiment illustrated in Figure 4 of 10 the drawings, one leaf of an ordinary hinge, indicated by the numeral 16, may be provided with a locking finger 17 integral with either the upper or the lower portion thereof and corresponding in every respect to the 15 fingers 8 and 14 of the previously described forms. It will be obvious that a recess must be formed in the door frame adjacent the companion hinge leaf to receive the finger 17.

From the foregoing description of the 20 invention, it will be evident that a door equipped with the auxiliary locking device cannot be opened even if the pintle pins of the hinges for the door are withdrawn, inasmuch as the locking finger of the device 25 engages the keeper upon the door jamb in a manner to preclude outward displacement of the hinged side of the door from its frame, the ordinary lock upon the door preventing similar displacement of the free side 30 of the door from the frame. Ordinarily, the provision of a single one of these devices located about midway of the height of a door will suffice, but, if desired, two or more of the devices may be employed upon the

door and they may be arranged in any manner found most convenient.

Having thus described the invention, what I claim is:

1. An auxiliary fastening device for a hinged door comprising an attaching plate 40 to be secured to the hinged edge of the door, and a locking finger projecting from the plate and, in the closed position of the door, engaging in a recess formed in the door frame, the said finger being of arcuate 45 form and tapered towards its free end and having one edge concentric to the axes of the hinges for the door whereby the prong will have wedging fit in the recess when the door is closed.

2. A fastener for a hinged door comprising a keeper plate adapted to be secured to the jamb of a door frame and in covering relation to a recess in the jamb and having a slot communicating with the recess, an attaching plate adapted to be secured to the hinged edge of the door, and a locking finger 55 projecting from the said attaching plate and tapered towards its free end and when the door is closed having its inner end portion 60 snugly fitting in the slot in the keeper plate and substantially filling said slot, said finger being of arcuate form and having one edge concentric to the axes of the hinges for the 65 door.

In testimony whereof I affix my signature.

PRESTON BELVIN. [L. s.]
